HAY BALER

James E. Bywater, Royal Oak, Mich., assignor to Ford
Motor Company, Dearborn, Mich., a corporation of Delaware

Filed July 9, 1963, Ser. No. 75,711

Term of patent 14 years

(Cl. D40—1)

Des. 199,798

The dominant features of my design reside in the full line portions.

I claim:

An ornamental design for a hay baler, as shown and described.
